UNITED STATES PATENT OFFICE.

WILLARD D. DOREMUS, OF WASHINGTON, DISTRICT OF COLUMBIA, ASSIGNOR
TO THE EAGLE LOCK COMPANY, OF TERRYVILLE, CONNECTICUT.

LOCK.

SPECIFICATION forming part of Letters Patent No. 243,872, dated July 5, 1881.

Application filed April 25, 1881. (Model.)

To all whom it may concern:

Be it known that I, WILLARD D. DOREMUS, of Washington city, District of Columbia, have invented a new and useful Improvement in Locks; and I do hereby declare that the following is a full, clear, and exact description of the same, reference being had to the accompanying drawings, forming part of this specification, in which—

10 Figure 1 is a view of the lock with the key-holder, its barrel, and the face-plate removed. Fig. 2 is a similar view with the tumbler which holds the bolt removed and the bolt projected. Fig. 3 is a section through the line xx of Fig. 1, the section passing also through the key-holder and its barrel. Fig. 4 is a face view of the key-holder and barrel.

15 My invention relates to an improvement in locks designed principally for drawers and cupboards, but applicable also to other uses.

In the above application of locks it frequently becomes desirable, when one's keys are misplaced or not convenient, to quickly lock the drawer or door, particularly when suddenly called away from the drawers of desks or those containing valuables.

20 The object of my invention is to supply this need; and to that end it provides a lock consisting of a bolt provided with a spring for driving it into the locking position, combined with a catch for holding the bolt withdrawn, and a depressible thimble, sleeve, or exposed surface arranged about the key-hole and adapted to be forced inwardly to allow the unlocked bolt to be shot from the action of the spring into a locking position without the application of the key, all as hereinafter more fully described.

25 In the drawings, A represents the back plate, and B the front plate, of a drawer or cupboard lock. In the right-angular edge of the back plate is arranged the sliding bolt C, whose shank portion is slotted and slides over a pin, a . In the front plate is formed a barrel, D, in which revolves a key-holder, while on one side of this are arranged a series of tumblers, b , forced toward the key-holder by individual springs c . These tumblers rest flat one upon another, and are pivoted upon the pin a , immediately above the shank of the bolt, while the other ends of the tumblers have straight

slots therein adapted to receive the lug d on the bolt whenever said slots are brought into proper registration by the key.

30 As so far described the lock does not differ substantially from one already in use. In applying my invention to the same I place at the rear end of the bolt a spring, E, whose normal tendency is to throw the bolt into its locking position. I then place upon the tumblers b an additional tumbler, b^2 , Fig. 1, having a right-angular slot in its end. This tumbler is pivoted upon the same center a with the other tumblers and has also a corresponding spring, c^2 , the effect of which is to throw the shoulder e of the tumbler in front of the lug d of the bolt, and hold the bolt against the tension of the spring E, so that it will stay unlocked when withdrawn by the key. When it is desired to lock the bolt by the key this supplemental tumbler is acted upon by the key and thrown back, like the other tumblers, until the lug a of the bolt has a free outward travel. Now, to effect the same result without the application of the key, I throw the catch or supplemental tumbler back by the following means: The key-holder G, which is slotted longitudinally and has its outer end exposed through the barrel D, I cause to have an end-wise as well as a rotary movement, and on the same I form a boss, thimble, ring, collet, or sleeve, having a conical end, f , and the conical end of this thimble is made to bear against the adjacent edge of the supplemental tumbler carrying the catch e , so that when the key-holder is thrust in by a pressure of the finger on its exposed face the conical surface acts like a cam and throws back the said supplemental tumbler and catch, and allows the spring E to shoot out the bolt.

35 In making use of my invention I do not restrict my invention to any particular form or application of spring E to the bolt, as any spring which will project the bolt can be used with my invention. I do not, moreover, limit myself to the particular form of the catch or supplemental tumbler for holding the bolt back. I may also apply my invention to any kind of lock.

40 Having thus described my invention, what I claim as new is—

1. A lock consisting of a bolt provided with

a spring for driving it into the locking position, combined with a catch for holding the bolt withdrawn, and a depressible thimble, sleeve, or exposed surface, arranged about the 5 key-hole, and adapted to be forced inwardly to withdraw the catch from the bolt when unlocked, and allow the bolt to be shot from the action of its spring into a locking position without the application of the key, substantially as shown and described.

2. A lock consisting of a bolt provided with

a spring for driving it into locking position, combined with a catch for holding the bolt withdrawn, and a thimble, sleeve, or exposed surface, arranged about the key-hole and having a conical inner end for direct engagement and release of the catch by a movement inward, as described. 15
